(57) **CLAIM**

The ornamental design for a television set, as shown and described.

DESCRIPTION

FIG. 1 is a front, right perspective view of a television set showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view of a portion of FIG. 1.

The dot-dot-dash broken line showing in FIGS. 1 and 8 is for the purpose of illustrating a partially enlarged view of FIG. 1 only and forms no part of the claimed design.

1 Claim, 8 Drawing Sheets(56)
